UNITED STATES PATENT OFFICE

LOUIS A. ERICKSON, OF WEST MCHENRY, ILLINOIS

LEVELING APPARATUS

Application filed June 5, 1929. Serial No. 368,680.

This invention relates to certain novel improvements in leveling apparatus and more particularly to leveling apparatus that may be used in connection with aircrafts and other similar mechanisms and has for its principal object the provision of an improved construction of this character which will be efficient and positive in use and economical in manufacture.

10 Another object of the invention is to provide a device of the above described character which will be arranged in a manner such that operation thereof will be automatic.

15 Another object of the invention is to provide an apparatus of the above described character in a manner such that it will operate both longitudinally and transversely.

20 A still further object of the invention is to arrange the apparatus in such a manner that it may be manually operated and to arrange the mechanisms so that the automatic operation may be rendered inoperative when the manual control is employed.

25 A still further object of the invention is to provide an apparatus of the above described character which will embody portions that may be operated simultaneously in opposite directions and to arrange the apparatus so that these mechanisms may be operated simultaneously in the same direction.

30 Other objects will appear hereinafter.

The invention consists in the novel combination and arrangement of parts to be hereinafter described and claimed.

35 The invention will be best understood by reference to the accompanying drawings, showing the preferred form of construction and in which:

40 Fig. 1 is a side elevational view depicting a preferred form of construction for my invention;

45 Fig. 2 is a top plan view of the device as illustrated in Fig. 1;

Fig. 3 is a longitudinal sectional view;

Fig. 4 is a transverse sectional view taken substantially on the line 4—4 on Fig. 1;

50 Fig. 5 is a sectional detail view of the means employed to operate the automatic leveling portions of my device;

Fig. 6 is a sectional view taken substantially on the line 6—6 on Fig. 5;

Fig. 7 is a sectional view taken substantially on the line 7—7 on Fig. 3;

Fig. 8 is a detail view showing the side 55 elevation of the longitudinal automatic leveling apparatus;

Fig. 9 is a front view of the device depicted in Fig. 8;

Fig. 10 is a diagrammatic view depicting 60 the electrical connections employed in the automatic leveling apparatus;

Fig. 11 is a front elevational view of the transverse leveling apparatus;

Fig. 12 is a sectional detail view taken sub- 65 substantially on the line 12—12 on Fig. 11;

Fig. 13 is a side elevational view of the apparatus depicted in Fig. 11;

Fig. 14 is a side elevational view showing 70 the arrangement employed for manually operating the mechanisms depicted in Figs. 8 and 9;

Fig. 15 is a detail view taken substantially on the line 15—15 on Fig. 14; and

Fig. 16 is a detail view taken substan- 75 tially on the line 16—16 on Fig. 13.

In the accompanying drawing I have illustrated my invention in association with an aircraft but it is to be understood that the apparatus might be associated with other 80 mechanisms such as for example boats or various forms including submarines. Applying the invention to such apparatus certain changes might be necessitated but these changes will be readily apparent to anyone 85 skilled in the art and are, therefore, believed to be within the purview of my invention.

In the drawings 10 generically indicates the main body of the aircraft with which my invention is associated. In the intermediate 85 portions of the body 10 I intend to arrange suitable passenger or freight carrying compartments but have not depicted these compartments in detail as any desired arrangement thereof may be made in accordance with the requirements to be met in the use of the craft with which my invention is associated. I have, however, shown a plurality of port holes 11 which may be associated with the device in the portion thereof to be devoted to 90

these compartments. As best illustrated in Fig. 3 an upper portion 12 is provided in the main body 10 at the forward end thereof and this upper portion is preferably arranged from horizontal alignment from the major portion of the main body 10 and a suitable curved configuration such as that indicated by 13 suitably interconnects this portion 12 with the main body 10. In the portion 12 and in the section of the main body 10 joining this portion 12 to the main portion of the body 10 I arrange the control apparatus as well as a portion which may be devoted to the operator of the craft. This portion of the apparatus will be known hereinafter as the control compartment 14. I provide in the body 10 suitable port holes such as 15 so as to afford the operator of the device an arrangement by which he will be enabled to view the course to be taken by the apparatus. Suitable wheel structures such as those indicated by 16 and 17 are arranged below the main body 10 at suitable points so as to facilitate the supporting and movement thereof over the surface of the earth and I preferably arrange the body 10 so that it will be substantially water tight in order that the device may be landed in water.

At the side of the body 10 I arrange wing structures 18 which are supported in a manner to be set forth presently. Arranged above the main body 10 are co-operating wing structures 19 and 20 which are supported on the housings 21 in a manner to be set forth presently. These wing structures co-operate to provide the lifting surface for the craft and also function to provide the leveling action to be described. Arranged at the rear end of the body 10 is the usual rudder structure generically indicated by 22 and a suitable elevator structure 23 is also provided adjacent this rudder 22 and these mechanisms are operated in a manner to be set forth hereinafter.

The housings 21 extend upwardly from the main body 10 at an acute angle thereto. As best illustrated in Fig. 4 a shaft 24 is supported in the upper ends of aligned housings 21. Intermediate the housings 21 a brace rod 25 is arranged which interconnects the shafts 24 in the various housings 21 so as to reenforce the same. Each of the co-operating wings 19 and 20 are rotatably fixed on the shaft 24. As best illustrated in Fig. 4 a crank 26 is fixed to cross braces 27 in the wing structure 20 and a link 28 extends from this crank arm 26 through the housing 21. A similar arrangement is provided in the wing 19 and when the links 28 are motivated in the manner to be set forth hereinafter it is apparent that the co-operating wings 19 and 20 may be moved about the shaft 24.

Extending out from the main body 10 are shafts 29 and 30 and the wings 18 are pivotally mounted on these shafts 29 and 30. A

cross brace 31 is arranged in the wings 18 and a crank arm 32 is fixed thereto. A link 33 is fixed to the crank arm 32 and the opposite end thereof is connected to members to be set forth hereinafter. A similar arrangement is provided in connection with the wing 18 and by motivating the links 33 the wings 18 may be angled relative to the horizontal.

As best illustrated in Fig. 3 in each of the housings 21 a bell crank 34 is pivotally mounted and the adjacent end of each of the links 28 is connected to one of the arms of these bell cranks. A rod 36 extends through the various housings 21 and each of the other arms of the bell cranks are connected to this rod 35 and it is to be understood that such a rod 35 extends on each side of the body 10 as best illustrated in Fig. 4. Other bell cranks such as 36 are arranged in the housings 21 and the links 33 are connected to one of the arms of these bell cranks. Rods 37 extend through the various housings 21 and the other of the arms of the bell cranks 36 are pivotally connected to these rods 37. It is manifest that if movement be imparted to the rods 35 and 36 simultaneously and in the same direction the co-operating wings 19 and 20 will be pivoted about the shaft 24 in the same direction. It is also manifest that if movement be imparted to the rods 35 simultaneously in opposite directions the wings 19 and 20 will be pivoted about the shaft 24 in opposite directions. It is also apparent that when movement is imparted to the rods 37 movement will be imparted to the wings 18 to pivot these wings about the shafts 29 and 30. The means for imparting movement to the rods 35 and 37 will now be described.

As best illustrated in Fig. 3 a housing 38 is supported from the portion 12 in the compartment 14. This housing is illustrated in detail in Figs. 5 and 6 and includes an upper wall 39 in which a suitable socket joint 40 is arranged at the mid-portion thereof. A ball 41 is mounted in the socket 40 and a pendulum rod 42 depends from this ball and has a weight 43 in the lower end thereof. Mounted adjacent the lower end of the housing 38 are four plates 44, 45, 46, and 47. These plates are disposed so that when the pendulum rod 42 is set in motion the ball 43 will engage one of the plates dependent upon the direction of movement and this arrangement is utilized in the manner to be set forth presently. A suitable electric connector such as that indicated by 48 extends through each of the side walls of the housing 39 and these connectors 48 are electrically connected to each of the plates 44, 45, 46, and 47. An electrical connector 49 is provided on the socket 40 for a purpose to be set forth presently.

By referring to Fig. 10 it may be seen that a suitable source of electric current such as the battery 50 and a conductor 51 extends be-

70

110

115

120

125

130

tween one terminal of this battery 50 and the connector 49. Co-operating pairs of electro-magnets indicated by 52 and 53, and 54 and 55 are provided. An armature 56 is arranged intermediate the electro-magnets 52 and 53 and equalized springs 57 and 58 serve to normally hold this armature 56 in a position intermediate the electro-magnets 52 and 53. An armature 59 is arranged intermediate the electro-magnets 54 and 55 and equalized springs 60 and 61 serve to hold this armature 59 in neutral intermediate position between the electro-magnets 54 and 55. A conductor 62 extends between the other terminal of the battery 50 and a connecting point 63. A conductor 64 extends between the connecting point 63 and one terminal of the electro-magnet 52. A conductor 65 extends between the connecting point 63 and one terminal of the winding of the electro-magnet 53. A conductor 66 extends between the connecting point 63 and one terminal of the winding of the electro-magnet 54. A conductor 67 extends between the connecting point 63 and one terminal of the winding of the electro-magnet 55. A conductor 68 extends between the other terminal of the winding of the electro-magnet 55 and the plate 44. A conductor 69 extends between the plate 46 and the other terminal of the winding of the electro-magnet 54. A conductor 70 extends between the plate 45 and the other terminal of the winding of the electro-magnet 52. A conductor 71 extends between the plate 47 and the other terminal of the winding of the electro-magnet 53.

In operation if the body 10 tilts in one direction as for example in the direction of the plate 44 the rod 42 will pivot in this direction by reason of the ball and socket connection including the ball 41 and the socket 40 and the ball 43 will engage the plate 44 which will close an electric circuit to the electro-magnet 55 in the following manner. Current will flow from the battery 50 through the conductor 51, connection 49, to the ball 41, rod 42, to ball 43, plate 44, through the connector 48 on said plate, to the conductor 68, through the winding of the electro-magnet 55, conductor 67, connecting point 63, conductor 62, to the battery 50. This energizing of the electro-magnet 55 by reason of the current flowing through the winding thereof will attract the armature 59 against the action of the spring 61 which will cause said armature 59 to pivot about the pivotal support 72 therefor and this action is utilized in a manner to be set forth presently to set in operation my improved leveling arrangement which will again restore the body 10 to normal horizontal position. As soon as the leveling apparatus is set in operation the body 10 will start to right itself which will cause the ball 43 to move from engagement with the plate 44 which will interrupt the

circuit to the winding of the electro-magnet 55 which will cause deenergizing thereof and, therefore, the spring 61 will be enabled to reposition the armature 59 in the position shown in Fig. 10. Should the body 10 be tilted in the opposite direction the ball 43 will engage the plate 46 and a circuit will be closed in a manner substantially similar to that set forth to the winding of the electro-magnet 54 which will cause the attraction of the armature 59 against the action of the spring 60. Similarly should the body 10 tilt in a direction such that the ball 43 is moved toward the plates 45 or 47 a circuit will be closed upon engagement of said ball with said plates to either the winding of the electro-magnet 52 or the winding of the electro-magnet 53 which will cause the attraction of the armature 56 by the deenergized electro-magnet against the action of either the spring 57 or the spring 58 and the armature 56 pivots about the pivotal support 73 therefor when moved. This movement of the armatures 56 and 59 is utilized in a manner now to be set forth to close a circuit to the mechanisms which operate my leveling apparatus.

In Figs. 3, 11, 12, and 13 I have depicted the arrangement employed for the leveling of my device transversely. This apparatus which is generically indicated by 74 includes a frame 75 which comprises parallel arms 76 and 77 and arms 78 and 79 which extend outwardly at right angles with respect to the arms 76 and 77 respectively. At the juncture of the arms 76 and 78, and 77 and 79 a substantially circular bearing 80 is formed. On the frame 75 a ledge is provided on which a motor 81 is arranged. Interiorly of the ring bearing 80 is a ring shaped member 82 which has formed on the inner periphery thereof on the upwardly disposed side a plurality of gear teeth 83. On the shaft 84 of the motor 81 is a pinion 85 which meshes with the gear teeth 83 and when the motor 81 is set in operation in a manner to be set forth presently the ring shaped member 82 is caused to move in the bearing 80.

Depending from the ring shaped member 82 opposite the gear teeth 83 is an arm 86. A substantially semi-circular rod member 87 is secured to the ends of the arms 78 and 79 and depends below these arms. A bearing 88 is secured to the arm 86 and the rod member 87 is extended through this bearing. Fixed on the rod 87 adjacent the ends thereof are collars 89 and 90. A coil spring 91 is disposed around the rod member 87 between the adjusting collar 89 and the bearing 88. A coil spring 92 is disposed around the rod member 87 between the adjusting collar 90 and the bearing 88. The springs 91 and 92 are equalized in order that they will normally act on the bearing 88 to hold the arm 86 in the neutral position depicted in Fig. 11.

A cross brace 93 extends across the compartment 14 and two vertically disposed bearings 94 and 95 are mounted on this cross brace 93. Rods 96 and 97 are extended through these bearings 94 and 95 and the lower ends thereof are pivotally connected at diametrical points to the member 82 as indicated at 98 and 99. When the ring shaped member 82 is moved in a manner to be set forth about the bearing 80 one of the rods 96 or 97 will be moved upwardly through the bearing supporting the same while the other of the rods will move downwardly through the bearing supporting the other rod. A bell crank 100 is pivotally mounted as indicated at 101 and includes an arm 102 that has a slot 103 provided in one end thereof. A pin 104 is fixed on the arm 96 and extends through the slot 103. The bell crank 100 also includes an arm 105 to which one of the rods 35 is pivotally connected as indicated at 106. A similar bell crank arrangement is associated with the arm 97 and is connected to the other of the rods 35. By referring again to the diagrammatic view Fig. 10 it may be seen that contacts 107 and 108 are arranged on one side of the armature 56 while the contacts 109 and 110 are arranged on the opposite side thereof. The contacts 108 and 109 are interconnected by a conductor 111. The contacts 107 and 110 are connected by a conductor 112. A conductor 113 extends between the conductor 111 and one terminal of the armature 114 of the motor 81. A conductor 115 extends between the conductor 112 and the other terminal of the armature 114. The current supplying leads which are connected to a suitable source of electric current are indicated by 116 and 117. In the event the main body portion 10 tilts in a direction such that the ball 43 moves into engagement with the plate 45 a circuit will be closed through the winding of the electro-magnet 52 which will cause the armature 56 to be attracted as has been set forth heretofore. This attraction of the armature 56 will move the contact plates 118 and 119 on said armature into engagement with the contacts 108 and 107 respectively. A conductor 120 extends between one terminal of the field coil 121 of the motor 81 and the conductor 117. A conductor 122 extends between the other terminal of the field coil 121 and is electrically connected to the contact plate 118. A conductor 123 electrically interconnects the contact plate 119 and the conductor 116. Therefore, when the contacts 118 and 119 engage the contacts 107 and 108 a circuit will be closed to the motor 81 which will cause operation of the motor 81 in a direction to be set forth. This circuit is as follows: conductor 117, conductor 120, field coil 121, conductor 122, contact plate 118, contact 108, conductor 111, conductor 113, armature 114, conductor 115, conductor 112, contact 107,

contact plate 119, conductor 123, to conductor 116. This as stated will cause operation of the motor 81 in one direction and this is utilized in a manner which will be set forth presently.

Should the main body portion 10 tilt in a direction such that the ball 43 will move into engagement with the contact plate 47 a circuit will be closed in the manner set forth through the winding of the electro-magnet 53 which will cause the armature 56 to be attracted by said electro-magnet 53 which will cause the contact plates 118 and 119 to engage the contacts 110 and 109 respectively. In this instance a circuit will be closed to the motor 81 in the following manner: conductor 117, conductor 120, field coil 121, conductor 122, contact plate 118, contact 110, conductor 115, armature 114, conductor 113, conductor 111, contact 109, conductor plate 119, conductor 123, to conductor 116. It is apparent in this latter instance that the current travels through the armature 114 in a direction opposite to the direction of travel thereof when the contacts 107 and 108 are engaged and this causes operation of the motor 81 in the opposite direction. This movement of the motor 81 is utilized in the following manner. When the ball 43 engages the contact strip 45 the motor 81 is set in operation in a manner such that the pinion 85 acts on the gear teeth 83 to move the ring 82 and the arm 86 in a direction such that the arm 86 will move toward the left as the device is viewed in Fig. 11. This movement of the ring 82 will move the arm 97 upwardly and the arm 96 downwardly. This movement of these arms is transmitted through the bell cranks connected thereto to the rods 35. Therefore, the rod 35 which is connected to the bell cranks 34 which in turn are connected to the wings 19 will be moved in a direction such that the wings 19 will be moved into the angular inclination thereof depicted in Fig. 3. At this same time the wings 20 will be pivoted through the action of the rod 35 connected thereto to move the wings 20 so that they will be inclined to the horizontal in an amount equal to the inclination of the wings 19 but in an opposite direction. If the device is associated with an aircraft as has been set forth it is apparent that the angular inclination of the wings 19 will be such that the air will act thereon in a direction so as to tend to tilt the body 10 and in view of the fact that the wings 20 are tilted in the opposite direction the air will act thereon to accent with action and, therefore, the device will be righted.

When the ball 43 engages the contact strip 47 the motor 81 will be operated in the opposite direction and this will cause the wings 19 to be moved into a position substantially similar to that described as being occupied by the wings 20 while the wings 20 will move into a position substantially similar to that

80

85

90

95

100

105

110

115

120

125

130

70

75

described as being occupied by the wings 19. Therefore, the air will act on these wings to again position the body 10 in normal position. It is, therefore, apparent that the device will 5 function to right the craft when the same tilts transversely. It is also manifest that at the time the ball 43 disengages either the plate 45 or the plate 47 that the equalized springs 91 and 92 will act to reposition the arm 86 and the remaining portions of the device in the 10 neutral position depicted in Fig. 11.

It is manifest that the motor 81 might be operated in a manner such that the arm 86 would be moved through too great a distance 15 and in order to prevent this condition I arrange on the rods 76 and 77 switch structures 124 and 125 which respectively include operating arms 126 and 127 that are arranged to be engaged at a predetermined time by the 20 arm 86. These switch structures 124 and 125 are arranged in the circuit at any desired point as for example that shown in Fig. 10.

In order to level the device when it is tilted from a longitudinal horizontal position the 25 following mechanisms are provided which are generically indicated by 128 and these mechanisms are illustrated in detail in Figs. 8 and 9. Brackets 129, 130, and 131 are provided for supporting a rod 132 that has a rack 133 30 provided thereon at substantially the point illustrated in Figs. 8 and 9. A motor 134 is supported by the member to which the brackets 129, 130, and 131 are secured. On the shaft 135 of the motor 134 a pinion 136 35 which meshes with the rack 133 is provided. A collar 137 is adjustably mounted on the rod 132 intermediate the brackets 129 and 130. A spring 138 is fitted around the rod 132 between the bracket 129 and the collar 137. A 40 spring 139 is disposed around the shaft 132 between the bracket 130 and the collar 137. The springs 138 and 139 are arranged so that they are equalized in order that they will act on the collar 137 to normally hold the rod 132 45 in the neutral position illustrated.

The motor 134 is controlled by the action of the armature 59 in the following manner. The armature 59 includes contact plates 140 and 141. Arranged on corresponding sides 50 of the contact plates 140 and 141 are contacts 142 and 143. Arranged on the opposite sides of the contact strips 140 and 141 are contacts 144 and 145. A conductor 146 interconnects the contacts 142 and 145 while a conductor 55 147 interconnects the contacts 144 and 143. A conductor 148 extends between the conductor 146 and one terminal of the armature 149 of the motor 134. A conductor 150 extends between the armature 149 and the conductor 147. A conductor 151 extends between one end of the winding of the field coil 152 of the motor 134 and the conductor 117. The conductor 153 is electrically connected 60 to the contact plate 140 and to the other end 65 of the field coil 152. A conductor 154 elec-

trically interconnects the contact plate 141 and the conductor 116. Limit switches 155 and 156 are provided in the circuit at substantially the point illustrated in Fig. 10. In Figs. 8 and 9 it is shown that these limit 70 switches are disposed adjacent the rod 132 and pins 157 and 158 extend outwardly from the rod 132 so as to respectively engage the operating levers 159 and 160 of the switches 155 and 156.

As is best illustrated in Figs. 1 and 3 the elevator 23 is mounted on a shaft 161 which extends transversely thereacross at substantially the center thereof in order that the elevator 23 may be tilted relative to the remaining portions of the craft. Cables 162 and 163 are connected to the elevator 23 on opposite sides of the shaft 161 and these cables 162 and 163 are connected to opposite ends of the rod 132 and the cables are directed 80 around suitably located sheaves so as to extend between these two points.

When the craft tilts in a direction such that the ball 43 moves into engagement with the contact plate 46 a circuit is closed to the winding of the electro-magnet 54 which causes the energizing thereof which causes the electro-magnet 54 to attract the armature 59. This moves the contact plates 140 and 141 into engagement with the contacts 142 and 143 and a circuit is closed to the motor 134 in the following manner. The current flows from the conductor 117, through the conductor 151, field coil 152, conductor 153, contact plate 140, contact 142, conductor 146, 90 conductor 148, armature 149, conductor 150, conductor 147, contact 143, contact plate 141, conductor 154, to conductor 116 which causes the motor 134 to operate in one direction. This movement of the motor is transmitted 95 through the shaft 135, pinion 136 to the rack 133. Movement imparted to the rack 133 causes the rod 132 to be moved downwardly and this movement is transmitted through the cable 163, to tilt the elevator 23 so that 100 the forward end thereof will be depressed, which will, therefore, reduce the effective surface thereof and, therefore, the rear end of the device will move downwardly so as to 105 reposition the body 10 in a horizontal plane.

When the ball 43 moves into engagement with the plate 44 a circuit is closed to the winding of the electro-magnet 55 which causes the attraction of the armature 59. This moves the contact plates 140 and 141 115 into engagement with the contacts 144 and 145. Therefore, a circuit will be closed to the motor 134 in the following manner. Current will flow from the conductor 117, through the conductor 151, field coil 152, conductor 153, contact plate 140, contact 144, conductor 147, conductor 150, armature 149, conductor 148, conductor 146, contact 145, contact plate 141, through conductor 154, to conductor 116. It is apparent that in this latter instance the 120 125 130

rod 152 will be moved upon operation of the motor 134 in a direction such that the movement thereof will be transmitted through the cable 162 to tilt the elevator 23 in a direction opposite to that heretofore set forth. 5 It is, therefore, apparent that this arrangement will automatically maintain the body 10 longitudinally level.

I have set forth the means employed for 10 automatically leveling my device but it is readily apparent that it would be advantageous to have these mechanisms arranged so that they may be manually operated. By referring to Figs. 3, 7, and 13 it may be seen that I arrange on one side of the pilot's seat 15 161^a a manually operable lever 162^b. This lever 162^b is supported in the following manner. Stationarily mounted bearings 163^a and 164 are provided to which a segment 165 is hingedly secured as at 166 and 167. The 20 segment 165 has a strip 168 extending thereacross and a bell crank lever arrangement comprising the arm 162 and an arm 169 is pivotally connected to this strip 168 as indicated at 170. By moving the lever 162 so that the 25 segment 165 pivots about the hinges 166 and 167 movement will be transmitted through the arm 169 to the link 170 which extends into the sleeve 171 which has a ball socket 172 provided thereon in which a ball 173 at the lower end of the arm 86 is arranged. Therefore, this rocking movement imparted through the lever 162 and the link 169 and the mechanisms connected thereto may be 30 utilized to cause the arm 86 to be moved in the same manner as when the same is actuated by the motor 81 and the device may, therefore, be used to maintain the apparatus 35 in a transversely level position. I have set forth that the wings 18 are arranged so that they may be tilted and this arrangement is utilized to cause the elevation of the craft when so desired. A plurality of notches or 40 ratchet teeth 174 are provided on the upper surface of the segment 165. Guide bearings 45 175 and 176 are arranged on the handle 162 and a rod 177 extends through these bearings and is acted on by a spring 178 to normally be forced downwardly in order to seat in one of the notches 174. A handle 179 is pivotally connected to the handle 162 as at 180 and by gripping this handle and moving the same about the pivotal support 180 the rod 177 may be moved upwardly. After the rod 50 177 has been moved upwardly the arms 162 and 169 may be pivoted about the support 170 therefor. At the lower ends of the arms 76 and 77 are balls 181 and 182 which are seated in sockets 183 and 184 that are carried by the arm 169. Therefore, when the 55 arm 169 is pivoted as set forth the entire structure supported by the arms 76 and 77 is moved upwardly. A bell crank comprising arms 185 and 186 is pivotally mounted as 60 at 187. A slot 188 is provided at the outer

end of the arm 186 through which a pin 189 on the arm 76 is extended. To the outer end of the arm 185 one of the links 37 is secured. The other of the links 37 is secured to a similar arm of a similar bell crank that is similarly attached to the rod 77. Therefore, when the arm 169 moves in a vertical plane the rods 76 and 77 are moved in vertical planes and also the rods 96 and 97. 75 This movement is, therefore, transmitted through the various bell cranks to the rods 35 and 37 which causes the wings 18 and 19 and 20 to be simultaneously pivoted in the same direction in equal amounts and, therefore, the device may be used to cause elevation of the craft. 80

A switch 190 is arranged on the arm 162 and an arm 191 thereof projects into a position such that it may be engaged by the collar 192 on the rod 177 and this switch 190 is 85 disposed in a position such that a circuit to the motor 81 is interrupted when the rod 177 is elevated.

On the side of the seat 161 opposite the lever 162 is a lever 193. This lever 193 which 90 is illustrated in detail in Figs. 14 and 15 is pivotally mounted at 194 for longitudinal movement in a vertical plane. The lever 193 is pivotally mounted as at 195 for pivotal movement in a transverse vertical plane. 95 Suitable cables 196 and 197 are connected to the lever 193 and when the lever 193 is moved about the pivotal support 195 movement is transmitted through either the cable 196 or the cable 197 to the rudder 22 to position 100 this rudder for a purpose well understood in the art.

When the lever 193 is pivoted about the support 194 movement thereof is transmitted through the cable 162 which is connected thereto in the manner indicated at 198 in Fig. 14 and obviously movement imparted to the cable 162^a will also be imparted to the cable 163 and, therefore, the mechanisms operated by these cables may be manually 105 operated.

On the lever 193 is a switch 199 which includes an operating handle 200. Pivotally mounted on the arm 193 is an operating handle 201 which includes an arm 202 that 115 engages the switch operating handle 200 when the handle 201 is moved to compress the spring 203. This switch 199 is arranged in the circuit to the motor 134 so as to interrupt the circuit thereto when the device is 120 being manually operated.

It is manifest from the foregoing description that I have provided a construction which may be arranged for either manual or automatic control and I have arranged this device so that it will function to maintain an aircraft or the like with which it is associated substantially level.

While I have illustrated the device in connection with an aircraft it is to be understood 130

that other mechanisms might be employed without departing from the purview of my invention.

If the device is used in connection with an aircraft as depicted a suitable power supplying member such as the internal combustion engine 204 is arranged in the compartment 14 and on the shaft 205 thereof a suitable propeller structure 206 will be arranged.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention what I claim as new and desire to protect by Letters Patent is:

1. In a device of the character stated, a main body, means for pivotally supporting wing members above said main body, means for pivotally supporting wing members at the sides of said main body, means for simultaneously pivoting said wing members at an angle with respect to the horizontal, said last named means including portions for independently pivoting the wing members at the sides of said main body, and other means for independently pivoting the wing members at the top of said body.

2. In a device of the character stated, a main body, means for pivotally supporting wing members above said main body, means for pivotally supporting wing members at the sides of said main body, means for simultaneously pivoting said wing members at an angle with respect to the horizontal, said last named means including portions for independently pivoting the wing members at the sides of said main body, and other means for independently pivoting the wing members at the top of said body, said last named means including separable means operable to pivot certain of last named wing members in a direction opposite to the direction in which other of said last named wing members are pivoted.

3. In a device of the character stated, a movable member, yieldable means for maintaining said movable member in a neutral position, rod members, means for supporting said rod members for parallel movement, means for connecting said rod members to said movable member, means for moving said movable member to move said rod members, said movable member moving said rod members in opposite direction, operable means, means for interconnecting said operable means and said rod members for moving said operable means in opposite directions when said rod members are moved, means for mov-

ing said rod members in the same direction whereby said operable means will be moved in the same direction, other rod members, means for interconnecting said last named means to said first named rod members whereby when said first named rod members are moved in the same direction said last named rod members will be moved simultaneously therewith, other operable means, and means for connecting said last named operable means to said last named rod members.

In testimony whereof I affix my signature.
LOUIS A. ERICKSON.
